US00D773684S

(12) **United States Design Patent** (10) **Patent No.:** **US D773,684 S**
Ketterer et al. (45) **Date of Patent:** **** Dec. 6, 2016**

(54) **CASSETTE**

(71) Applicant: **ACCELERATE DIAGNOSTICS, INC.**, Tucson, AZ (US)

(72) Inventors: **Matthew Ketterer**, Tucson, AZ (US); **Matthew Mette**, Marana, AZ (US)

(73) Assignee: **Accelerate Diagnostics, Inc.**, Tucson, AZ (US)

(**) Term: **14 Years**

(21) Appl. No.: **29/525,006**

(22) Filed: **Apr. 24, 2015**

(51) LOC (10) Cl. **24-02**

(52) U.S. Cl.

USPC **D24/227**

(57) **CLAIM**

The ornamental design for a cassette, as shown and described.

DESCRIPTION

FIG. 1 is a perspective view of a cassette in an environment of use showing our new design;

FIG. 2 is a front view of the cassette of FIG. 1;

FIG. 3 is a rear view of the cassette of FIG. 1;

FIG. 4 is a right side view of the cassette of FIG. 1;

FIG. 5 is a left side view of the cassette of FIG. 1;

FIG. 6 is a top view of the cassette of FIG. 1;

FIG. 7 is a bottom view of the cassette of FIG. 1;

FIG. 8 is a perspective view of the cassette of FIG. 1 in an alternative environment of use;

FIG. 9 is a front view of the cassette of FIG. 8;

FIG. 10 is a rear view of the cassette of FIG. 8;

FIG. 11 is a right side view of the cassette of FIG. 8;

FIG. 12 is a left side view of the cassette of FIG. 8;

FIG. 13 is a top view of the cassette of FIG. 8; and,

FIG. 14 is a bottom view of the cassette of FIG. 8.

The broken lines depict environmental subject matter only and form no part of the claimed design.

1 Claim, 10 Drawing Sheets
